UNITED STATES PATENT OFFICE

2,670,935

RADIATOR HANGER

Thomas L. Arnold, West Hartford, Conn., assignor to The Vulcan Radiator Company, Hartford, Conn.

Application September 16, 1950, Serial No. 185,276

6 Claims. (Cl. 257—133)

1

This invention relates to a radiator hanger and more particularly to a hanger for finned type radiators such as commonly hung on walls of rooms.

An object of this invention is to provide such a hanger which is economical to produce, highly efficient and which will materially facilitate the installation of radiators.

A further object is to provide a hanger on which the radiators may be easily and conveniently adjusted to a desired pitch for drainage.

A further object is to provide a radiator hanger having means carried thereon for supporting a cover for the radiator and thereby rendering unnecessary conventional cover hanging strips such as have heretofore been independently mounted on walls adjacent the radiator for supporting the covers thereover.

A still further object of the invention is the provision of a hanger which will permit the operation of installing a radiator to be performed from a convenient position in front of the hanger and thereby eliminate inconvenience and difficulty such as commonly found in installing radiators with hangers of conventional form.

A still further object is the provision of a hanger which is particularly adapted for use in baseboard radiators.

Further objects and advantages of this invention will be more clearly understood from the following description and the accompanying drawings in which:

Fig. 1 is a sectional side view of a radiator showing my improved bracket in use therewith and partly in central vertical section.

Fig. 2 is a front view of the said radiator partly broken away to show the construction of the bracket.

Fig. 3 is an enlarged plan view of my improved radiator bracket.

Fig. 4 is a side view of the bracket on a reduced scale.

Fig. 5 is a front view of said bracket.

Fig. 6 is a front view of said bracket in a slightly modified form.

Fig. 7 is an enlarged fragmentary side view of the upper portion of the radiator, partially in vertical section, illustrating the sealing strip employed therewith.

In the embodiment illustrated in the drawings, the numeral 5 indicates the lower portion of a wall on which my improved radiator is mounted. The said radiator commonly comprises an outer elongated cover 6 having an upwardly inclined

2

portion 7 with a downwardly extending lip 8 at the upper end thereof, a front wall portion 9, and a bottom portion in the form of an inwardly extending flange 10. A series of radiators 11, comprising a plurality of spaced heat transfer fins 12 mounted upon a conductor 13, are contained within the said cover and supported by my improved hanger.

It will be noted that the cover 6 has a series of perforations in the angled portion 7 and that the free edge of the flange 10 is spaced from the wall to permit circulation of air upwardly through said cover and between the fins of the radiators.

My improved hanger is indicated at 14 and, in the form shown, comprises a top section having a wall engaging portion 15 and a lower section having the wall engaging portion 16 and the bottom portion 17 which extends outwardly therefrom and has, at its outer end, an upright projection 18.

The intermediate portion 19 of the hanger, between the said upper and lower portions thereof, is spaced forwardly from the plane of the wall engaging portions and has a longitudinal slot 20 therein which receives the shanks of a plurality of carriage bolts 21, each of which supports an L-shaped radiator supporting bracket having an upright mounting portion 22, a forwardly extending bottom 23 and an upright cover engaging portion 24.

My improved hanger is attached to the wall by means of a screw or bolt 25, which extends through the portion 15 of the top section, and a similar screw or bolt 26 which extends through the portion 16 of the bottom section.

Each of the supporting brackets is secured to the hanger by a single carriage bolt 21 which is slidable along the slot 20 to thereby render the bracket easily adjustable for positioning the radiators at the desired height and pitch.

In the form illustrated, my improved hanger is, for the purpose of economy, preferably constructed with the top and bottom sections thereof joined together by means of parallel bars 27 and 28 which are secured to the said top and bottom sections by being welded thereto, as indicated at 29, with the said parallel bars resting upon the tops of the portions 15 and 16 and being thereby elevated from the plane of the wall engaging portions and providing a space between them and the surface of the wall, as indicated at 30, to accommodate the heads of the carriage bolts 21 and prevent movement of said bolts out of the slot 20. By constructing my im-

proved hanger in the manner above described, I eliminate the necessity of special and costly tools such as would be required for producing the slot 20 in a unitary hanger construction.

In the embodiment shown there is provided, upon each of the supporting brackets, a U-shaped supporting member 31 which is laterally slidable upon the bottom portion 23 of the bracket and is secured thereto by means of a fastening 32 that extends through a slot 33 in the bottom of the said supporting member. A plate 34 of brass, or other non-corrosive material, is provided between the said U-shaped supporting member and the bottom portion 23 so as to facilitate movement of the supporting member upon the said bracket and prevent binding, such as commonly caused by reason of rust or the like, and thereby permit sliding movement of the supporting member under the influence of the expansion and contraction of the conductors 13.

The top section of my improved hanger is provided with a cover hanger bar 35 which is secured at the top of the said section and spaced from the surface of the wall 5 as clearly illustrated in Fig. 1. This bar 35 receives the downwardly extending lip 8 of the cover and thereby supports the cover along the surface of the wall and renders unnecessary the use of conventional hanger strips, such as have heretofore been independently secured to the wall for supporting the radiator covers, and thus simplifies the operation of installing the radiator and materially reduces the cost thereof. At the same time, the said bars 35, being movable with the hangers as they are adjusted for height, provide the proper fit of the cover on the hanger and eliminate the necessity of separately adjusting the conventional cover hanger strips heretofore used.

The said top section is preferably also provided with a downwardly and forwardly angled extension 35-a so as to firmly support the angled upper portion 7 of the cover.

In order to eliminate the discoloration of wall surfaces, such as commonly occurs along the tops of conventional forms of wall hung radiators, I provide a sealing strip 36, preferably of sponge rubber or the like, between the lip 8 of the cover and the surface of the wall. This strip prevents the heated air from passing between the cover and the surface of the wall and thereby prevents discoloration of the wall surface.

In mounting a radiator installation with my improved hanger, the required number of carriage bolts are first inserted through the slot 20 and the hanger is then secured to the wall by means of bolts 25 and 26. The supporting brackets are then secured to said hanger by means of the said bolts with the use of a nut on each of the bolts for fastening the portions 22 of the brackets against the front surfaces of the parallel bars 27 and 28. The radiators are then placed upon the brackets and may each be easily adjusted for height and drainage by simply loosening the nut on the screw 21 of the respective bracket and lowering or raising the said bracket. It will be noted that the portion 22 of the hanger extends upwardly sufficiently to permit the carriage bolt 21 to be located over the top of the radiator so that it becomes easily accessible over the radiator from a convenient position in front of the installation.

After the radiator units have been hung and adjusted with my improved hangers, the cover 6 is hooked over the hanger bar 35 and the lower portion 10 of said cover is secured to the bottom

section 17 of the hanger by means of a screw 37 and washer 38.

The said cover may also be secured at the upper portion thereof by means of a screw 39 which is threaded into the downwardly angled extension 35-a on the top section of the hanger.

My improved bracket provides an important advantage when used at the joints between sections of the cover 6 where it is desirable to have a joining strip 40, which follows the outer contour of the cover 6. The hanger is, therefore, provided with two adjacent threaded openings 41-41 to receive screws 42-42 which project through the joining strip and each of which extends through an opening adjacent the edge of each section of the cover so that the said sections are tied together by the said screws and thereby firmly held in alignment. At the bottom of the said joining strip, a single screw 37-a may be used although, if desired, two spaced screws may also be used as in the upper section.

My improved radiator hangers materially simplify and facilitate the installation of radiators for the reason that they may be easily secured to a wall in approximately the position desired, by means of the two screws 25 and 26, and the radiator units may be afterwards accurately adjusted for height and pitch by merely loosening the nuts on the carriage bolts 21, adjusting the brackets to accurately position the radiators and then again tightening the said nuts.

From the above description, it will be clearly understood that I have provided an improved radiator hanger which is rugged in construction, and which is adapted to support both the radiators and the covers thereof as a complete unit, whereby the position of the cover with relation to the radiator unit is always maintained irrespective of any adjustment which is made in the positioning of the hangers.

It will be also understood that my improved radiator hanger permits accurate adjustment from a convenient and comfortable position in front of the radiator by rendering the said carriage bolts 21 readily accessible from such a position both before and after the radiator units are mounted upon the supporting brackets of the hangers.

I claim:

1. A radiator hanger comprising an elongated, wall-engaging body portion having at least one pipe supporting bracket attached thereto, and an angled portion extending downwardly and forwardly from the upper end of said body portion and over said bracket to thereby provide a force resisting, cantilever support for a radiator cover.
2. A radiator hanger comprising an upper and a lower section, an intermediate section, at least one bracket adjustably mounted upon said intermediate section for supporting a radiator unit, an upright projection at the top of said hanger for hanging a cover thereon, an extension projecting downwardly and forwardly from the upper section for supporting the upper portion of said cover, a forwardly extending portion at the bottom of said hanger for positioning the lower portion of the cover, and means on said bracket adapted to abut the inner surface of the front portion of said cover to thereby firmly position the said front portion to prevent the inward movement thereof.
3. A radiator hanger comprising an upper and a lower section, an intermediate section, an angled portion extending downwardly and for-

wardly from the said upper section for supporting a cover over the radiator unit, an extension upon the said bottom section for positioning the lower portion of said cover, at least one supporting bracket adjustably secured to said intermediate section, a forwardly extending portion on said bracket, a member for supporting a radiator unit moveably mounted on said forwardly extending portion, and a perpendicular projection at the end of said forwardly extending portion of the bracket adapted to abut the front portion of the cover and thereby prevent the inward movement thereof.

4. A radiator hanger having an upper and a lower section, an intermediate section, at least one supporting bracket on said intermediate section for supporting a radiator unit on said hanger, a downwardly and forwardly projecting extension on said upper section for supporting the upper part of a radiator cover, and an elongated, upwardly directed element on said upper section projecting above said extension and spaced from the vertical plane of the rear surface of the upper section to receive a downwardly projecting lip on a radiator cover.

5. In a radiator including a heat transfer unit mounted upon a wall, a cover extending over said

unit and having an edge portion with a downwardly extending lip running along and adjacent to the said wall; a resilient sealing strip positioned between said lip and wall.

6. In a radiator including a heat transfer unit mounted upon a wall, and a cover extending over said unit and having an edge portion running along and adjacent to the said wall; a resilient sealing strip positioned between the said edge portion and wall.

THOMAS L. ARNOLD.
